CHARLES E. BRIDGES, OF CHICAGO, ILLINOIS, ASSIGNOR TO BURGESS-NORTON COMPANY, OF GENEVA, ILLINOIS, A CORPORATION OF ILLINOIS.

WHEEL.

1,139,951.

Specification of Letters Patent. Patented May 18, 1915.

Application filed March 11, 1912. Serial No. 683,140.

To all whom it may concern:

Be it known that I, CHARLES E. BRIDGES, a citizen of the United States, and a resident of Chicago, in the county of Cook and 5 State of Illinois, have invented certain new and useful Improvements in Wheels; and I do hereby declare that the following is a full, clear, and exact description thereof, reference being had to the accompanying 10 drawings, and to the letters of reference marked thereon, which form a part of this specification.

This invention relates to wheels more especially adapted for small vehicles, such 15 as children's go-carts, baby carriages, and the like.

One of the objects of the invention is to provide a wheel which may be simply and economically manufactured and which, by 20 reason of its design and construction, shall have a maximum amount of strength for its weight and also a certain degree of 25 silency.

A form of wheel embodying the principles of the present invention is hereinafter described and is illustrated in the accompanying drawings, in which—

Figure 1 is a view in side elevation thereof; Fig. 2 is a radial section through the 30 hub, being taken on the line 2 of Fig. 5; Fig. 3 is a transverse section through one of the spokes, being taken on the line 3 of Fig. 1; Fig. 4 is a section through the rim, being taken on the line 4 of Fig. 1; Fig. 5 is a view in perspective showing the parts 35 constituting the hub and an adjacent portion of one of the spokes, disassembled; Fig. 6 is an axial section on the line 6 of Fig. 2; Fig. 7 is a view similar to Fig. 2, but showing 40 a modified form of the construction.

As shown in said drawings, in Figs. 1 to 45 6, inclusive, the wheel is made entirely of metal, and comprises a rim 10, a hub 11, and a plurality of spokes, here shown as five in number, 12, 12. The latter are longitudinally curved, in arcs of approximately 180°, and are sprung into position between the rim and the hub from which latter they extend tangentially. In order to add stiffness 50 to these spokes, each is also curved in cross-section, or fluted, as indicated at 14, throughout its entire length, having substantially the same cross-sectional contour as the rim 10, which is shown as an ordinary 55 grooved rim of familiar form adapted to

receive a rubber tire; and each spoke, throughout a portion of its outer length, is parallel to the rim 10, the inner surface of which it embraces (Fig. 4). Each spoke is also formed with integral marginal flanges, 60 or webs 15, 15, which taper in width, the complete spokes being of substantially the same width at its inner end as the hub 11, and the webs continuing of full width, as indicated at 16, 16, for a small distance outward, whence, continuing outward, they narrow in width and disappear at the outer end of the spoke. When all the parts are 65 in place the inner end portions of the spokes are arranged transversely of the hub 11, so that the said spokes extend tangentially 70 from the said hub and each spoke lies with its inner end meeting and extending at an angle from one of its neighbors, as shown in Fig. 2; and, in order that the spokes may 75 lie as closely together as possible at the hub, the curved center portion of each spoke is extended a sufficient distance, as shown at 24, to enter and fit closely within the 80 concave groove of the spoke which it meets, (Fig. 3). The spokes, shaped or constructed as described, will preferably be made of sheet metal, swaged or stamped to give the desired form.

Referring now to the parts constituting 85 the hub of the wheel, these comprise a metal tube 28, on the ends of which are secured a pair of annular members 30, 30 in the form of radial flanges; and each of said radial flanges is formed with a cylindric flange 90 32 at its periphery, extending inward or in a direction toward the opposite end of the hub. In each flange 32 are cut a number of notches 33, 33, corresponding to the number of spokes, and in the marginal extensions 95 or webs 16, 16 of each spoke, at a distance from the inner end of such spoke corresponding to the radius of the flanges 30, are cut similar notches 35, 35.

The complete device is assembled as follows: The spokes being all placed in their proper relation to each other, either within the rim or not, as desired, the tube 28 is placed in the pentagonal opening formed by their meeting ends, the length and curvature of the spokes being such that if they are within the rim this opening must be enlarged by the insertion of a suitable wedge-shaped, implement to admit the tube, whereby the spokes are all somewhat compressed. 100 105 110

The hub is then completed by placing the rings 30, 30 upon its ends, with their notches engaging with the notches in the spokes, and expanding the ends of the tube to retain the rings in place, after which the spokes may be sprung into position within the rim, if they have not previously been placed therein. When the parts are thus assembled, the marginal flanges on the spokes rest in contact with the end portions of the tube 28, as clearly seen in Fig. 6. The notched members 30, 30 constitute securing means in the ends of the hub, by which the inner ends of the spokes are held in fixed relation to the hub. A wheel constructed and arranged as described, possesses sufficient rigidity and strength for a variety of uses without any further securing means whatever, but where greater strength is desired the outer end 20 of each spoke may be additionally secured to the rim 10, as by rivets 40, 40.

In Fig. 7 is shown the inner or center part of a wheel similar in all respects to that above described, except that the inner 25 end of each spoke, instead of extending transversely of the tubular part of the hub, extends part-way around the hub, being curved at its inner end in the reverse direction to the curve through the rest of its 30 length. As shown in said figure, 45 indicates the tubular portion of a hub similar to that above described, from which extend spokes 47, 47, likewise similar to those above described; except that each spoke is re- 35 versely curved through a portion of its length 48, 48, at its inner end, thereby over-lapping an adjacent spoke. They are simi- 40 larly notched in their edges and similarly secured in place by rings at the ends of the tube having notched cylindric flanges at their peripheries.

I have shown and described one practical form of my improved wheel; but the same may be variously modified in practice without departure from the spirit of my invention, and I do not desire to be limited to the exact features of construction illustrated and hereinbefore set forth, except so far as the same may be defined in the appended 50 claims as parts of my invention.

I claim as my invention—

1. In a wheel, the combination with a rim, of a plurality of spokes, the inner end portions of said spokes terminating in off- 55 set relation to the axis of the wheel, and meeting to form a hub, the inner end of each of said spokes abutting against the lateral surface of an adjacent spoke, and means for rigidly connecting the inner portions of 60 said spokes comprising a continuous connecting member secured to each of said spokes adjacent to their inner ends.

2. In a wheel, the combination with a rim, of a plurality of spokes, the inner end por- 65 tions of said spokes terminating in offset

relation to the axis of the wheel, and meeting to form a hub, the inner end of each of said spokes abutting against the lateral surface of an adjacent spoke, and an annular ring having interlocking engagement with 70 said spokes adjacent to their inner ends.

3. In a wheel, the combination with a rim, of a plurality of spokes, the inner end portions of said spokes terminating in offset relation to the axis of the wheel, the inner 75 end of each of said spokes abutting against the lateral surface of the end portion of an adjacent spoke, an annular ring having interlocking engagement with said spokes adjacent to their inner ends, and a sleeve inserted within the opening formed by the inner end portions of said spokes.

4. In a wheel, the combination with a rim, of a plurality of spokes, each of said spokes terminating at its inner end in offset relation to the axis of said wheel and in abutting relation to an adjacent spoke, an annular ring having interlocking engagement with said spokes adjacent to their inner ends, and a sleeve inserted within the opening formed at the inner ends of said spokes, said sleeve having rigid connection with said annular ring and tangential bearing with the said spokes adjacent to their ends.

5. In a wheel, the combination with a rim 95 and a hub, of a plurality of spokes bearing tangentially at their ends upon said hub and rim, the inner end of each spoke abutting against the adjacent spoke, and connecting means rigidly secured to the hub 100 and in interlocking engagement with the margins of said spokes.

6. In a wheel, the combination with a rim and a hub, of a plurality of longitudinally curved spokes, each spoke being curved in 105 cross-section and adapted to partially embrace said rim at its outer end, being widened and notched at its inner end and having its said inner end rounded to fit against the side face of an adjacent spoke.

7. In a wheel, the combination with a hub and a rim having a convexed inner surface, of a plurality of longitudinally and transversely curved spokes in tangential bearing at their outer ends with said rim, the same 115 fitting within the curved outer end portion of the spoke and secured thereto, and the inner end of each of said spokes bearing tangentially upon said hub and in abutting relation to an adjacent spoke, and connecting 120 means in interlocking engagement with said spokes.

8. In a wheel, the combination with a rim and a hub, of a plurality of longitudinally curved spokes, each of said spokes bearing 125 tangentially at its inner end upon the hub and in abutting relation to an adjacent spoke, and a radial flange at each end of the hub, each radial flange having an inwardly extending annular flange having in- 130

terlocking engagement with said spokes adjacent to their extremities.

9. In a wheel, the combination with a rim and a hub, of a plurality of longitudinally curved sheet metal spokes, each of said spokes being curved in cross-section and provided with tapering marginal flanges, said flanges being widest at the inner end of said spokes and provided with a plurality of annularly arranged notches, each of said spokes bearing tangentially upon said hub at a point adjacent to its inner end and in abutting relation at its end with an adjacent spoke, radially extending flanges rigidly connected to the ends of said hub and provided with inwardly extending cylindric flanges and notches formed in the margins of said cylindric flanges having interlocking engagement with the notches of said spokes.
10. In a wheel, the combination with a hub and a rim semicircular in cross-section, of a plurality of longitudinally and transversely curved sheet metal spokes in tangential bearing at their outer ends with the

said rim, the same fitting within the curved outer end portion of the spoke and secured thereto, and at their inner ends with said hub, each of said spokes extending slightly beyond its point of tangency and in abutting relation with the surface of an adjacent spoke, tapering marginal flanges on said spokes, being widest at their inner ends and provided with annularly arranged notches formed in the said flanges, radial flanges rigidly connected at the ends of said hub, provided with inwardly extending cylindric flanges having notches formed in the margins thereof, said notches having interlocking engagement with the notches of the 40 said spokes.

In testimony, that I claim the foregoing as my invention I affix my signature in the presence of two witnesses, this 5th day of March A. D. 1912.

CHARLES E. BRIDGES.
